TYPESETTING MACHINE COMPANY, OF NEW YORK, N. Y., A CORPORATION OF
NEW YORK.

AUTOMATIC STOPPING MECHANISM FOR LINE-CASTING MACHINES.

1,173,887.

Specification of Letters Patent. Patented Feb. 29, 1916.

Application filed May 27, 1913, Serial No. 770,280. Renewed August 17, 1915. Serial No. 46,016.

To all whom it may concern:

Be it known that I, SAMUEL E. SPERRY, a citizen of the United States, residing at Woodhaven, in the county of Queens and State of New York, have invented new and useful Improvements in Automatic Stopping Mechanism for Line-Casting Machines, of which the following is a specification.

10 This invention relates to improvements in machines of the linotype class and is applied to the mechanism for stopping the machine should a line of matrices for any reason be improperly presented to the mold.

15 The primary object of the invention is to provide stopping mechanism which is actuated by the molds to automatically interrupt the operation of the machine should a line of matrices be improperly presented to 20 the mold and is capable of use with a mold wheel carrying four molds as well as one carrying one or two molds.

To this end, the invention consists in certain improvements and combinations and 25 arrangements of parts, all as will be herein-after more fully described, the novel features being pointed out particularly in the claims at the end of the specification.

In the accompanying drawings:—Figure 30 1 is a front elevation of a portion of a machine of this class showing the mold-carrying disk or wheel and the coöperative parts of the machine; Fig. 2 shows the parts in Fig. 1 as viewed from the left, certain 35 of the parts being in section; Fig. 3 is a detail enlarged view of parts of the stopping mechanism as shown in the preceding figures; Figs. 4, 5 and 6 are views similar to Fig. 2, but showing the parts of the machine in different positions.

Similar parts are designated by the same reference characters in the several views.

The accompanying drawings show the present invention as applied to a line composing and line casting machine of the well known linotype class, wherein each line of matrices and spacers is carried to and from the casting level by a reciprocatory elevator and the mold in which the type-bar or slug 50 is to be cast is moved to and from the line of matrices while the latter is at the casting level.

In the present instance 1 designates the

mold-carrying disk or wheel having four molds 2 mounted thereon. 55

3 designates the elevator commonly known as the first elevator which is guided to slide vertically on the vise frame 4 and the vise cap 5 fixed thereto, and this elevator has an overhanging head 6 at its upper end which is provided with jaws 7 adapted to receive and support a line composed of matrices M and spacers S. The line of matrices and spacers is received by the elevator while the latter occupies the position shown in Figs. 1 and 2 as is well known, and the line of matrices and spacers is lowered by the descent of the elevator to a position between the jaws of a vise 8 which latter operates in a well known way to clamp and confine 70 the line in an endwise direction. The mold-carrying wheel or disk 1 is mounted usually on a slide which operates at appropriate intervals to carry the appropriate mold against the line preparatory to the casting 75 operation and to retract the mold from the line after the cast has been made. Fig. 4 shows the elevator in its lowered position and the line of matrices at the proper level in relation to the mold to allow the mold to 80 advance toward and into engagement with the line of matrices and spacers. Each mold is formed with a groove 9 adapted to receive and coöperate with the lugs or ears on the matrices whereby correct alinement 85 of the matrices is obtained. Should the elevator for any reason fail to bring the line to the proper casting level, the mold will strike the lower lugs on the matrices and crush or damage them unless the machine 90 is stopped before the mold comes against the matrices. Means, therefore, has been provided for stopping the machine automatically should the elevator fail to reach a position where the matrices occupy the 95 proper casting level. In the present construction, a vertically movable rod 10 is shown for this purpose, the upper end of this rod extending through the vise cap 5 whereby it may be engaged and depressed 100 by the head 6 of the elevator, and the lower end of this rod is in a position to coöperate with a lever 11, the latter being connected to the main clutch which controls the operation of the machine. This rod 10 is held 105 normally and yieldingly in its upper pos-

tion by a tension spring 12, and it is provided with a tooth or projection 13 which is arranged to coöperate with a plunger 14. This plunger 14 is reciprocable longitudinally in a cross-member of the vise frame 4, as shown in Figs. 1 and 2, and is provided with a compression spring 15, one end of which abuts against a screw 16, this spring acting normally to move the plunger 14 in a direction away from the rod 10 and toward the mold wheel. When the elevator descends to a point where the line of matrices and spacers will occupy the proper casting level, the head 6 of the elevator will then rest on top of the vise cap 5 and the rod 10 will be depressed by the head 6 of the elevator to a point where the tooth or projection 13 will be below the level of the plunger 14, and when the mold wheel is shifted forward to bring the appropriate mold into casting position against the line of matrices and spacers, the bottom mold on the mold-carrying wheel will bear upon and shift the plunger 14 forwardly and its forward end will pass over the tooth or projection 13 on the rod 10, as shown in Fig. 6. If, however, the elevator for any reason fails to descend to a point where the line of matrices and spacers will occupy the proper casting level, then the forward motion of the plunger 14 (under the influence of the mold wheel) will cause the forward end of the plunger 14 to press against the rear side of the rod 10, thereby deflecting this rod and causing the lever 11 which is acted on thereby to disengage the main clutch and interrupt the operation of the machine, thereby avoiding damage to the matrices or to any other part of the machine. Such operation is well known in machines of this class and is described in the patent to O. Mergenthaler, No. 436,532, dated September 16, 1890.

In machines of this class, the mold wheel is not only advanced or moved forwardly for the casting operation, but is also advanced or moved forwardly when the slugs are ejected from the mold and trimmed, and this second or intermediate advancing movement of the mold wheel occurs while the elevator is in an upper position. Inasmuch as the elevator cannot act upon the rod 10 while it is in raised position, it is necessary, especially where four molds are used upon the mold wheel, to provide means for preventing action of the plunger 14 upon the rod 10 whereby the running of the machine will not be interrupted during the slug-ejecting operation although the stop mechanism will interrupt the running of the machine should the elevator fail to correctly present the matrices to the mold. The present invention provides simple and effective means for obtaining these results whereby the stop mechanism is operative when the

mold is advanced for the casting operation and is rendered inoperative when the mold is advanced at the time of the slug-ejecting operation. In the present construction, the forward end of the plunger 14 is provided with a pin 17 and is formed with a recess 18 behind said pin. A shaft 19 is mounted in a bracket 20 secured to one of the cross-members of the vise frame 4, and a pair of arms 21 and 22 are fixed to the shaft 19, the arm 22 having a pin or dog 23 suspended therefrom by a pivot. The link 24 which operates the justifier 25 is also provided with a cam lug or projection 26 which is arranged on the forward side of the link and is adapted to coöperate with the arm 21 whereby the operation of the stopping means for the machine is controlled.

The operation of a machine equipped with the present invention is, briefly, as follows:—The parts normally occupy the position shown in Figs. 1 and 2, the elevator being then in a position to receive a line composed of matrices and spacers. At this time the bar 25 which serves to drive up the wedge spacers S occupies a position slightly above its lowermost position, and the lug or projection 26 on this link then engages the arm 21 of the controlling device, thereby holding the pendant pin or dog 23 up clear of the pin 17 in the plunger. In the next operation, the elevator descends and lowers the line of matrices and spacers to the casting level and the mold is then advanced against the line whereupon the cast is made. Fig. 6 shows the parts in this position, the plunger 14 having passed over the tooth or projection 13 on the rod 10 which latter is pushed down to its lowermost position by the head on the elevator. The justifier 25 is then driven up against the wedge-shaped spacers S by the link 24, carrying the lug or projection 26 past the arm 21, and allowing the pin or dog 23 to descend by its own weight and assume a position behind the pin 17, as shown in Fig. 6. While the casting operation is proceeding, the link 24 descends to its lowermost position, the lug 26 thereon passing the arm 21 and momentarily raising the pin or dog 23, but permitting the latter to again drop into a position behind the pin 17. The mold is next retracted to the position shown in Fig. 4, but the plunger 14 does not return with the mold for the reason that it is retained by the pin or dog 23, the latter bearing against an abutment 27 formed on the vise frame to sustain the thrust of the spring which actuates the plunger 14. After the mold has been retracted, the elevator rises and carries the line to the distributing mechanism, and hence the elevator no longer acts on the rod 10. The mold wheel or disk is rotated to bring the mold containing the cast slug to the ejecting position and is

also advanced again during the slug-ejecting operation and while the elevator is in raised position. If the plunger 14 were not retained in forward position by the pin 23 to prevent rising of the rod 10, this advancing movement of the mold wheel for the slug-ejecting operation would cause the lowermost mold on the mold wheel to push the plunger 14 against the rear of the rod 10 and thereby stop the machine. However, such is prevented, as the plunger 14 is retained by the pin or dog 23, the tooth or projection 13 on the rod 10 engaging beneath the plunger whereby the rod 10 is held in its lowermost position and hence the advancing of the mold disk for the slug-ejecting operation does not disturb the operation of the machine. The position of the parts at the time the mold wheel is advanced for the slug-ejecting operation is shown in Fig. 5. After the slug has been ejected, the mold wheel is retracted and the machine assumes the normal position shown in Figs. 1 and 2, the link 24 of the justifying mechanism then rising to a point where the lug or projection 26 thereon will act upon the arm 21, lifting the suspended pin or dog 23 clear of the pin 17 and thereby allowing the plunger 14 to spring back clear of the tooth or projection 13 on the rod 10 and permitting the latter to rise. This cycle of operations is repeated for the next casting and slug-ejecting operations, the plunger 14 being in condition to push the rod 10 forward and thus stop the machine if this rod is not depressed to the proper point by the elevator when the latter descends to bring the line to the casting level.

I claim as my invention:—

40 1. In a machine of the linotype class, the combination of an elevator for bringing a line of matrices and spacers to casting position, a mold-carrying member movable forwardly at intervals for casting a slug and for ejecting the cast slug, justifying mechanism operative to expand the spacers, a device actuated by the forward movement of the mold-carrying member for stopping the machine should the elevator fail to reach the casting position, and means actuated by the justifying mechanism to prevent operation of the stopping device when the mold-carrying member moves forwardly to eject the slug.

55 2. In a machine of the linotype class, the combination of an elevator for bringing a

line of matrices and spaces to casting position, a mold-carrying member movable forwardly at intervals for casting a slug and for ejecting the cast slug, justifying mechanism operative to expand the spacers, a device actuated by the forward movement of the mold-carrying member for stopping the machine should the elevator fail to reach the casting position, and a dog controlled by the justifying mechanism for retaining the stopping device in actuated position until after the slug-ejecting operation has been performed.

3. In a machine of the linotype class, the combination of an elevator for bringing a line of matrices and spacers to casting position, a mold-carrying member movable forwardly at intervals for casting a slug and for ejecting the cast slug, justifying mechanism operative to expand the spacers, means for stopping the machine embodying a member movable into a predetermined position by the elevator when the latter reaches casting position, and a plunger actuated by the forward movement of the mold-carrying member into casting position for operating said member to stop the machine when the elevator fails to reach the casting position, and means controlled by the justifying mechanism for retaining said plunger in actuated position until after the mold-carrying member has advanced to eject the slug.

4. In a machine of the class described, the combination of an elevator movable to carry a line of matrices and spacers to casting position, a mold wheel carrying a plurality of molds and movable forwardly to carry a mold thereon into casting position against the line and also movable forwardly to eject a cast slug, justifying means for expanding the spacers, a device actuated by one of the molds on the mold wheel when the latter is moved forwardly for stopping the machine if the elevator fails to reach the casting position, and means actuated by the justifying means to prevent operation of the stopping device by one of the molds on the mold wheel when the latter moves forwardly to eject a slug.

In testimony whereof I have hereunto set my hand in presence of two subscribing witnesses.
